UNITED STATES PATENT OFFICE.

HOWARD M. DUDLEY, OF PHILADELPHIA, PENNSYLVANIA.

DYEING-MACHINE.

1,332,489.

Specification of Letters Patent.

Patented Mar. 2, 1920.

Application filed October 26, 1917. Serial No. 198,567.

To all whom it may concern:

Be it known that I, HOWARD M. DUDLEY, a citizen of the United States, residing in the city of Philadelphia, county of Philadelphia, and State of Pennsylvania, have invented certain new and useful Improvements in Dyeing-Machines, of which the following is a full, clear, and exact specification.

10 My invention relates to dyeing machines and refers particularly to machines suitable for the dyeing of textile fibers, and like materials, by means of a circulating liquid.

One object of my invention is a device 15 whereby textile fibers may be dyed evenly and uniformly while in a compressed condition.

Another object of my invention is a device whereby a liquid may be passed uniformly 20 and thoroughly through a compressed mass of fiber.

Another object of my invention is a device whereby the formation of channels may be prevented while passing a liquid through a 25 compressed mass of fiber.

Another object of my invention is a device whereby the condition of the treated fiber may be determined without interrupting the process of treatment.

30 Another object of my invention is a device compressing a testing device whereby the condition of the treated fiber may be accurately determined without opening the dyeing chamber.

35 These and other objects of the device of my invention will be evident upon a consideration of my specification, drawings and claim.

40 Great difficulty is experienced in obtaining even and uniform dyeings of textile fibers in those machines in which the fiber is treated while under pressure to the action of a dyeing liquid. Under these conditions the liquid has a tendency to form channels 45 or passages through the fiber, through which more liquid passes than through other portions of the fiber, thus causing uneven results.

50 It is evident that when fiber is compressed between two plates having openings with parallel sides, the liquid forced through the openings will be impinged in a series of liquid columns against the fiber forcing itself therethrough in a series of channels,

the intermediate portions of the mass being 55 less affected by the liquid.

It is further evident that unless the liquid pressure is absolutely equal upon all parts of the foraminous plates, more liquid will be forced through some of the holes than 60 through others causing uneven dyeings.

It is further evident that an equal liquid pressure must be maintained at all times throughout the entire mass.

My device accomplishes all of these three 65 vital elements of successful dyeing and presents a method whereby all portions of the fiber will be treated equally by the impinged liquid whereby the formation of channels is prevented, whereby the liquid pressure will 70 be absolutely equalized over the entire foraminous plate and whereby a uniform liquid pressure will be maintained throughout the fiber mass.

In order to equalize the liquid pressure 75 over the entire foraminous plate, I pass the liquid into the device through a series of conduits distributed below a foraminous plate, thus distributing the liquid as evenly as possible, from these the liquid passes 80 through a foraminous plate, thus breaking up any currents that have been formed, into a chamber from which it passes through a second foraminous plate into the fiber mass. This chamber between the two foraminous 85 plates causes a complete equalization of the liquid pressure and allows an absolutely uniform and equal amount of liquid to pass through all portions of the fiber mass.

In order to prevent the formation of 90 channels through the mass due to the impinging of liquid columns upon the fiber, the foraminous plate of my device upon which the fiber rests consists of a series of inwardly projecting members, thus presenting 95 a maximum of fiber surface to the action of the liquid and causing it to penetrate the entire mass in an equal and complete manner.

In order to maintain a uniform liquid 100 pressure throughout the entire fiber mass, the two foraminous plates of my device, between which the fiber is compressed, are exactly similar in construction, the exit of the liquid from the mass therefore being under 105 the same conditions as its entrance into the mass.

By means of my testing device, the condi-

tion of the dyed fiber may be determined at any time without opening the dyeing chamber or interrupting the operation, the value of which device is evident.

5 I also provide means whereby the liquid may be passed in opposite directions through the fiber when desired.

Having thus broadly described my invention: I give the following example of 10 one form of my device.

In the particular form of my device shown in the accompanying drawings, similar parts are designated by similar numerals:

15 Figure 1 is a side plan view partly in cross-section.

Fig. 2 is a cross-section through the line 2—2 of Fig. 1.

20 Fig. 3 is a cross-section through the line 3—3 of Fig. 1.

Fig. 4 is a broken detail top plan view of one of the inner foraminous plates.

Fig. 5 is a cross-section through the line 5—5 of Fig. 4.

25 Fig. 6 is a broken top plan view of one of the outer foraminous plates.

Fig. 7 is an enlarged cross-section of a testing device.

30 Fig. 8 is a cross-section of a modified form 30 of the top and bottom members of my device.

Fig. 9 is a cross-section through the line 9—9 of Fig. 8.

35 Fig. 10 is a broken top plan view of a modification of one of the inner foraminous plates.

Fig. 11 is an end view of Fig. 10.

40 Fig. 12 is a broken top plan view of a modification of one of the outer foraminous plates.

Fig. 13 is an end view of Fig. 12.

The device of my invention, as illustrated, 45 comprises a receptacle having the side wall 20, within which is the foraminous plate 21, resting upon the annular offset 22 of the side wall 20. Spaced above the plate 21, and supported therefrom by the annular member 23, is a foraminous plate 24. The bottom 25 of the receptacle contains a series of converging tubes 26, 26, 26, the interior ends of 50 the tubes 27, 27, 27 being extended upwardly. The outward ends of the tubes 26, 26, 26 terminate in a chamber 28 within the extended portion 29 of the receptacle. Re-

55 movable from and slidable within the receptacle is a foraminous plate 30. A removable top 31 contains a series of converging tubes 32, 32, 32 similar to those in the bottom 25, the interior ends of the tubes 33, 33, 33 being extended downwardly. The outward ends of the tubes 32, 32, 32 terminate in a chamber 34 within the extended portion 35 of the top. The top 31 also carries the foraminous plate 36, and the 60 downwardly extended portion 37 of the top

is capable of abutment upon the plate 30. Screw bolts 38, 38 passing through openings in the flange 39 of the top 31 and threaded in the holes in the flange 40 of the wall 20 allow of the top being forced downwardly 70 into the receptacle. Bolt eyes 41, 41 are inserted into the top 31 as a means for raising the top.

A testing tube, shown in cross-section in Fig. 7 is similar and proportionate to the 75 larger device and comprises the wall 42 and the foraminous plates 43, 44, 45 and 46 similar to the plates 36, 30, 24 and 21 respectively. The threaded hollow members 47 and 48, threaded with the interior of the 80 wall 42 enable the compression of the fiber 101. The lower portion of the wall 42 is connected with the pipe 49 by means of the bushing 50. The pipe 49 carries the valve 51 and is connected with the chamber 52 85 by means of the conduit 53. The upper portion of the wall 42 is connected with the pipe 54 by means of the bushing 55. The pipe 54 carries the valve 56 and is connected to the chamber 93 by the conduit 58. By 90 means of the bushings 50 and 55, the testing device can be removed from connection with the pipes 49 and 54 to allow of charging the same or of examining the contents.

Plates 24 and 30, as shown in Figs. 4 and 95 5, consist of a series of serrated rings 60, 60, supported by the members 61, 61.

Plates 21 and 36, as shown in Fig. 6, consist of a plate having circular openings 63, 63 therein.

100 The extended top member 35 is connected to the pipe 64 which in turn is connected to the pipe 65 by means of the flange coupling 66. The pipe 64 carries the valve 67 and is connected to the discharge chamber of the 105 pump 68 by means of the slide bushing 90.

The extended bottom member 29 is connected to the pipe 69, which carries the valve 70, and is connected to the discharge chamber of the pump 68.

110 The pipe 71 connecting the members 35 and 29 carries the valves 72 and 73 and is connected with the pipe 74 emptying into the top of the reserve tank 75.

The bottom of the reserve tank 75 is connected to the pipe 76, carrying the valve 77 and connected to the receiving chamber of the pump 68. A pipe 78 carrying the valve 79 connects a dissolving tank, not shown, with the receiving chamber of the pump 68. 115 A pipe 80, carrying the valve 81, enters the chamber 28.

In the modification of the top member 31 and the bottom member 25, as shown in Figs. 8 and 9, the tubes 26, 26 and 32, 32 are 120 replaced by the troughs or conduits 82, 82, open at the portion toward the interior of the receptacle.

The modification of the plates 24 and 30, shown in Figs. 10 and 11, comprises a series 125

of parallel and intercepting bars 84, 84 having extended points or members 85, 85.

In the modification of the plates 21 and 36, shown in Figs. 12 and 13, the holes 86, 86 are square instead of round.

The operation of the device is as follows:—

The fiber mass 100 is placed within the receptacle and upon the plate 24. Plate 30 is then placed upon the fiber mass, and the top 31 lowered into place. The pipe 64 is connected to the pipe 65 by means of the coupling 66, and the member 35 connected to the pipe 71 by means of the nipple 91. The screw bolts 38, 38 are then inserted and screwed down, the member 37 pressing the plate 30 inwardly until the desired pressure is obtained upon the fiber mass, the pipe 65 sliding into the bushing 90, and the nipple 91 being turned to take care of the downward movement of the top. The testing device is charged with the fiber mass 101, and placed in position. All of the valves are closed with the exception of valves 79, 70, 51, 56 and 72, and the pump 68 started. The liquid thus passes from the dissolving tank, not shown, through the pipe 78, the pump 68, the pipe 69, the pipes 26, 26, the chamber 52, the plate 21, the chamber 92, the plate 24, the fiber chamber and the fiber 100 therein, the plate 30, the chamber 57, the plate 36, the chamber 93, the tubes 32, 32, the pipes 71 and 74 into the reserve tank 75. When sufficient liquid has been introduced into the reserve tank, the valve 79 is closed and valve 77 opened; the liquid then having a continuous circulation in the direction mentioned above. At the same time the liquid passes upwardly through the testing device and the fiber 101 therein.

When it is desired to reverse the flow of the liquid, valves 70 and 72 are closed and valves 67 and 73 are opened, thus allowing the liquid to pass in a reverse direction through the device. From time to time, as desired, 45 the condition of the fiber in the testing device may be determined by closing valves 51 and 56 and removing the device as previously described. The liquid may be drained off through the pipe 80, and water may be 50 introduced for washing the fiber by means of the pipe 94 carrying the valve 95.

I do not limit myself to the particular size, shape, number or arrangement of parts as described and shown, all of which may be 55 varied without going beyond the scope of my invention as described and claimed.

What I claim is:—

In a dyeing machine, in combination, a receptacle having imperforate sides, two foraminous plates within and extending across the receptacle, a fiber chamber between the two plates and the sides of the receptacle, means for increasing and decreasing the size of the fiber chamber, two foraminous plates 65 spaced outwardly from the first two plates, a reserve tank, a conduit connecting the upper portion of the receptacle with the reserve tank, a pump, a conduit connecting the reserve tank with the pump, curved tubular 70 members above and below the foraminous plates so arranged that a liquid may be continuously forced through the tubular members, the plates, the fiber chamber and the reserve tank in either direction. 75

Signed at New York city in the county of New York and State of New York this 15 day of October, 1917.

HOWARD M. DUDLEY.
